CLAIM

The ornamental design for an upper for a shoe, as shown and described.

DESCRIPTION

FIG. 1 is a side elevational view of one side of an upper for a shoe showing my new design;

FIG. 2 is a side elevational view of the other side of the upper for a shoe as shown in FIG. 1;

FIG. 3 is a front elevational view of the upper for a shoe as shown in FIG. 1;

FIG. 4 is a rear elevational view of the upper for a shoe as shown in FIG. 1; and

FIG. 5 is a top plan view of the upper for a shoe as shown in FIG. 1.

The broken line showing of a sole FIGS. 1-4 is for illustrative purposes only and forms no part of the claimed design.

FIG. 1

FIG. 4

FIG. 3

FIG. 5
